DESIGN FOR A FABRIC

Louis R. Bressler, Southampton, Mass., assignor
to Stanley Home Products, Inc., Westfield, Mass., a corporation of Massachusetts

Application December 9, 1948, Serial No. 150,047

Term of patent 14 years

(Cl. D92—1)

To all whom it may concern:

Be it known that I, Louis R. Bressler, a citizen of the United States, residing at Southampton,
in the county of Hampshire and Commonwealth
of Massachusetts, have invented a new, original,
and ornamental Design for a Fabric, of which the following is a specification, reference being had to the accompanying drawings, forming part thereof.

The figure is a plan view of a fabric, showing
my new design.

I claim:

The ornamental design for a fabric, as shown.
LOUIS R. BRESSLER.
